UNITED STATES PATENT OFFICE.

GUSTAV O. WILMS, OF MILWAUKEE, WISCONSIN, ASSIGNOR TO THE RELIANCE COMPANY, OF MILWAUKEE, WISCONSIN, A CORPORATION OF WISCONSIN.

EQUALIZING DEVICE FOR COMPRESSION RESISTORS.

Application filed June 16, 1922. Serial No. 568,873.

To all whom it may concern:

Be it known that I, GUSTAV O. WILMS, a citizen of the United States and resident of Milwaukee, in the county of Milwaukee and State of Wisconsin, have invented new and useful Improvements in Equalizing Devices for Compression Resistors, of which the following is a description, reference being had to the accompanying drawings, which are 10 a part of this specification.

This invention relates to certain new and useful improvements in electric current controlling devices and refers more particularly to means for applying equal pressures 15 to a multiplicity of current controlling devices of the compression resistor type.

One object of this invention is to provide a pressure mechanism for applying equal pressures to two or more resistors of the 20 compression type in such a manner as to secure the greatest mechanical advantage as the operation of compressing the resistors is continued.

This invention has for another object to 25 utilize the reacting force of one of a group of compression resistors to produce pressure against one or a group of other resistors.

It is a further object of this invention to 30 provide means for producing pressure on a resistor of the compression type whereby the reacting force of a member independent of the resistor is employed to produce pressure thereon whereby maximum mechanical advantage is obtained as the compression 35 of the resistor is continued.

With the above and other objects in view which will appear as the description proceeds, my invention resides in the novel construction, combination and arrangement of 40 parts substantially as hereinafter described and more particularly defined by the appended claims, it being understood that such changes in the precise embodiment of the hereindisclosed invention may be made 45 as come within the scope of the claims.

In the accompanying drawings, I have 50 illustrated one complete example of the physical embodiment of my invention constructed according to the best mode I have so far devised for the practical application 55 of the principles thereof, and in which:

Figure 1 is a side view of the upper end of several groups or series of compression type resistors equipped with my improved 60 pressure producing means;

Figure 2 is a top view of the means for equalizing the pressure applied to the resistors of one group, said view being taken on the plane of line 2—2 of Figure 1, and

Figure 3 is a transverse sectional view 60 taken through Figure 2 on the plane of line 3—3.

Referring now more particularly to the accompanying drawings, the numerals 5 and 6 designate evener bars carried by one 65 end of a rocker arm or saddle 7 pivotally mounted, as at 8, between a pair of spaced connected levers 9, the levers 9 having their inner ends pivotally mounted between a bracket 10 and their outer ends connected 70 by a block 11 having pintles 12 swivelled therein.

The evener bars are free to rock about pivot pins 13 and between the bars, adjacent one end, a U-shaped bracket 14 is secured. Pivoted between the evener bars, as at 15, adjacent the opposite end, a distance from the center of pivot 13 approximately one half of that from said pivot to the center of bracket 5, is a channel bar 16 which 80 extends to an equal distance from each side of its pivot. Rock studs 17 extend from the channel bar at equal distance from pivot 13 and from bracket 5 and are engageable with resilient pressure plugs 18 which extend through the bushings of compression resistor units 19 and make contact with the resistor disc therein (not shown).

As illustrated in Figures 2 and 3, the other end of the saddle or rocker 7 carries 90 evener mechanism similar to that previously described and further description is therefore deemed unnecessary. It will also be apparent, by inspection of Figure 1, that evener mechanism of the character described 95 is provided for each group of resistor units 19.

An adjustable pull rod 20 extends through each swivel block 11 mounted between the free ends of each pair of levers 9 so that a 100 downward pull of the rods will be equally transmitted to all the resilient pressure plugs 18. Each pull rod 20 is threaded in an adjustable yoke end 21 which is bifurcated and pivoted to the outer end of the longer, substantially horizontal arm 22 of a bell crank 23, the same being fulcrumed on a pin 24 carried by a stationary spider 25. The shorter, substantially vertical arm 26 of each bell crank has the outer end of one 110

member or link 27 of a toggle pivoted thereto, the other ends of said links meeting at a common point and being connected by a pivot 28 with an adjustable yoke 29 in 5 which one end of a pull rod 30 is threaded.

From the above it will be apparent that force applied to pull rod 30, to the toggle pivot or joint 28 and at right angles to an imaginary line drawn through the pins 24, 10 will be transmitted equally to the bell cranks 23 and thereby to levers 9. It is also apparent that as the angle between the members 27 of the toggle becomes greater, i. e. as the toggle straightens out under downward pull on rod 30, the mechanical advantage increases.

When the discs (not shown) within the resistance units have reached the limit of compression, it is highly desirable to apply 20 additional pressure upon the rock studs 18 as it has been found that such additional static pressure reduces the ohmic resistance of the columns of discs (not shown). To vary the resistance of these columns is the 25 object of subjecting them to pressure. When the resilient contacts have reached the limit of compression, which they will do before the toggle links reach the angle of 180 degrees, the force applied through the 30 pull rod 30 imparts a turning movement on the bell cranks equal to the length of members 27 multiplied by the horizontal component of the force applied through the 35 toggle link. The horizontal components of the forces producing the turning movements of the bell cranks are in opposite directions and, therefore, the reacting against one of the horizontal components is the horizontal 40 component acting against the other bell crank.

What I claim as my invention is:

1. In a device of the character described including two compressible resistors, a pair of link members, means pivotally connecting the inner ends of the link members to provide a toggle joint, means connecting the outer ends of the link members with the resistors whereby straightening of the toggle joint compresses the resistors utilizing the 45 reacting force of one resistor to produce pressure on the other, and means for actuating the toggle joint.

2. In a device of the character described including two compressible resistors and a compression member for each resistor, a stress applying member for each resistor, means connecting one end of each stress applying member with the adjacent compression member, means connecting the other 55 ends of the stress applying members, whereby the reacting force of one resistor is utilized to produce pressure against the other, and an actuating member connected with said last mentioned means, whereby actuation of the actuating member imparts an

equal stress on the resistors through the medium of the compression members, stress applying members and means connecting the stress applying members.

3. A device of the character described, 70 comprising substantially independent compression members for actuating compression resistors, two rods connected one with each compression member, an actuating member, and means connecting the actuating member with the rods and utilizing the reacting force of one resistor to produce pressure against the other.

4. A device of the character described, 75 comprising substantially independent compression members for actuating compression resistors, two rods, one rod being adjustably connected with each compression member, an actuating member, and means connecting the actuating member with the rods and utilizing the reacting force of one resistor to produce pressure against the other.

5. A device of the character described, 80 comprising compression members for actuating compression resistors, bell cranks pivoted at their apex one adjacent each compression member, means connecting one arm of each bell crank with the adjacent compression member, an actuating member positioned medially of the bell cranks, and a connection between the actuating member and the other arms of the bell cranks.

6. A device of the character described, 85 comprising compression members for actuating compression resistors, bell cranks pivoted at their apex one adjacent each compression member, means connecting one arm of each bell crank with the adjacent compression member, an actuating member positioned medially of the bell cranks, and a 90 connection between the actuating member and the other arms of the bell cranks.

6. A device of the character described, 100 comprising compression members for actuating compression resistors, bell cranks pivoted at their apex one adjacent each compression member, means connecting one arm of each bell crank with the adjacent compression member, an actuating member positioned medially of the bell cranks, and a connection between the actuating member and the other arms of the bell cranks.

7. A device of the character described, 105 comprising a compression member for actuating a compression resistor, a bell crank pivotally mounted at its apex and having a substantially horizontal and a substantially vertical arm, a connection between the horizontal arm of the bell crank and the compression member, an actuating member, a link having one end pivotally connected with the actuating member and its other end connected with the vertical arm of the bell crank, and a second link having one end pivotally connected with the actuating member and its other end connected with a support, said links being normally out of longitudinal alignment whereby movement of the actuating member to bring the link in longitudinal alignment will compress the resistor.

8. In a device of the character described,

the combination with groups of compression resistors and pressure evening means for imparting pressure to the units of each group, of a long and a short armed bell crank for 5 each group and pivotally secured at its apex, pull rods connecting the long arms of the bell cranks with the adjacent pressure evening means, a second pull rod mounted between the bell cranks, and a toggle connection 10 between the short arms of the bell cranks and the second pull rod and including links pivoted to the bell crank short arms and to the second pull rod.

9. A device of the character described,

comprising a supporting frame, a compression type resistor unit mounted therein, a compression member for actuating the resistor, a bell crank pivoted in the frame at its apex, means connecting one arm of the bell crank with the compression member, 15 a toggle connected with the other arm of the bell crank, and means for operating the toggle to move the bell crank on its pivot and actuate the compression member to compress the resistor unit. 20

25 In testimony whereof I affix my signature.

GUSTAV O. WILMS.
